The invention relates to a counter having n stages each containing an element having two conductive states, each state of the counter exhibiting a specified distribution of the conductive states of the elements, which counter is returned to its initial state in case an input pulse out of a series of n pulses fails to appear, because in such a case a gating circuit lets pass a reset pulse in order to effect the distribution of conductive states corresponding to this initial state.

Such a counter is known from the British Patent Number 587,655, completely accepted May 1, 1947. In this counter a separate generator ensures the generation of the reset pulses. Measures had to be taken further, in order that the generator pulses and the input pulses of the series appear synchronously. The circuit is only usable, if the intervals between two successive input pulses are of uniform length and if enough pulses are available to realize said synchronism. Further the succession of the various series will have to be such that this synchronism need not be adjusted again for every new series.

According to the invention the above-mentioned disadvantages are removed in such a way that the input terminal of a network also containing an element having two conductive states is connected to each of the output terminals of at the most $n-1$ successive stages, in such a way that the element in such a network changes its conductive state as soon as the conductive state of the element in the associated stage changes in a certain sense, the element in the network reassuming after a delay the original conductive state, and that moreover the output terminals of the networks are so connected to the input terminals of the gating circuit that the reset pulse resulting from the said return to the original conductive state of the element in the network is only allowed to pass, if in none of the other networks the element is in the other conductive state.

Such a counter or distributor provided with a discriminator against isolated pulses or pulse pairs can e.g. be used in a scanning device for a registration bearer according to the U.S. patent application 828,646 filed July 21, 1959. This registration bearer is provided with three marking stripes above and/or below each of the figures to be scanned, these figures being scanned in the upper half as well as in the lower half in the three successive places indicated by the marking stripes. The information bits thus obtained from each figure are stored successively in 3×2 memory circuits by means of a distributor having three stages. By providing networks according to the invention, the distributor is protected against pulses originating from the edge of the paper, folds in the paper, perforations, etc., i.e. after such disturbances the distributor returns to the initial state, in order to ensure the recording of the bits of the next figure in the right way.

The invention will be described in detail, reference being had to the annexed drawing, which shows a schematic wiring diagram of an embodiment of the invention for a distributor in which the n number of stages are three and the associated $(n-1)$ networks are two; the stages and networks containing pnp transistors.

The distributor stages contain transistors X, Y and

Z, of which the emitters are connected to points of fixed potential; the collectors via conductor rails 1, 2 and 3, respectively, and via separate resistors R₁, R₂ and R₃ to points of fixed potential; and the bases each to a separate circuit. Each such separate circuit contains a capacitor, C₁, C₂ and C₃, respectively, both plates of which are connected to both a rectifier G₂₁—G₂₂, G₂₃—G₂₄, and G₂₅—G₂₆ and on the other hand to a resistor R₂₁—R₂₂, R₂₃—R₂₄, and R₂₅—R₂₆ to points of fixed potential. Moreover the left-hand plates of these three capacitors are connected via separate rectifiers G₂₇, G₂₈ and G₂₉, respectively to the input terminal A of the distributor and via separate rectifiers, G₁, G₅ and G₉, respectively, to conductor rails 3, 1 and 2. The right-hand plates of these three capacitors C₁, C₂ and C₃ are each connected via a separate rectifier G₃₁, G₃₂ and G₃₃ to the base of the associated transistors X, Y and Z, respectively, this base also being connected on one hand via a resistor R₂₇, R₂₈ and R₂₉ to a point of fixed potential and on the other hand via resistors R₃₁, R₃₂ and R₃₃ and rectifiers G₃₄, G₃₅ and G₃₆ to a point which is connected in its turn via resistors R₃₄, R₃₅ and R₃₆ to a point of fixed potential and via rectifiers G₂ and G₃, G₆ and G₇, and G₁₀ and G₁₁, respectively, to conductor rails 2 and 3, 1 and 3, and 1 and 2, respectively, but moreover as far as transistors X and Y are concerned, via a rectifier, G₄ and G₈, respectively, to a rail conductor 4.

In introducing the networks according to the invention, it has been started from that the initial state of the distributor, that is, the state in which transistors X and Y are non-conducting and transistor Z is conducting. Now the stages containing transistors X and Y are provided with networks containing transistors P₁ and P₂, respectively. The emitters of these transistors P₁ and P₂ are connected to points of fixed potential too. The collectors are each connected via a separate resistor to a point of fixed potential. The bases are each connected to a separate circuit containing a capacitor, C₄ and C₅, respectively.

The left-hand plates of these capacitors C₄ and C₅ are each connected on one hand via a rectifier G₄₁ and G₄₂ and on the other hand via a resistor R₄₁ and R₄₂ to points of fixed potential. They are connected moreover via rectifiers, G₁₂ and G₁₃, respectively, to rails 1 and 2, respectively. The right-hand plates of these condensers C₄ and C₅ are each connected via a rectifier G₄₃ and G₄₄ to a point of fixed potential and via a second rectifier G₄₅ and G₄₆ to the bases of the associated transistor, which is also connected to the tapping point of a potentiometer R₄₂—R₄₃ and R₄₄—R₄₅.

The collectors of transistors P₁ and P₂ are connected via rectifiers, G₁₄ and G₁₅, respectively to the left-hand plate of a capacitor C₆.

This left-hand plate is connected on one hand via a resistor R₅₀ and on the other hand via a rectifier G₅₀ to points of fixed potential. The right-hand plate of the condenser C₆ is connected to a tapping on a potentiometer R₅₁—R₅₄ as well as to the rectifier G₁₆ to a tapping on a further potentiometer R₅₃—R₅₄ as well as to the base of a transistor Q, of which the emitter is connected again to a point of fixed potential and the collector via a rectifier G₁₇ to a point B. The point B is connected on one hand via a resistor R₅₅ and on the other hand via a rectifier G₁₈ and two resistors R₅₆—R₅₇ in series to points of fixed potential. The connecting point between the rectifier and this potentiometer R₅₆—R₅₇ is connected to the left-hand plate of a capacitor C₇, the right-hand plate of which is connected to a point of fixed potential.

The connecting point between the two resistors of

potentiometer $R_{56}-R_{57}$ is connected to the base of a transistor R, of which the collector is connected to the above-mentioned rail conductor 4.

If the networks P_1 and P_2 and conductor rail 4 are left out of consideration for the moment, the following brief survey of the working of the distributor, which is known in itself can be given: In the initial state, transistors X and Y are non-conducting, and transistor Z is conducting, so conductor rails 1 and 2 have a negative potential with respect to conductor rail 3.

If there arrives a positive pulse at input terminal A, transistor Z becomes non-conducting, since rectifier G_9 is supplied with a negative potential, so capacitor C_3 will pass the positive pulse to the base of transistor Z. As a result of this transistor X will become conducting. The fact is that the positive pulse from input terminal A has no effect on it, because the left-hand plate of capacitor C_1 has already a positive potential via rectifier G_1 . Due to the change-over to the non-conducting state of transistor Z, however, rectifier G_3 is from that moment on supplied with a negative potential; rectifier G_2 has already a negative potential. The potential of the base of transistor X falls, so that transistor X becomes conducting. Transistor Y remains non-conducting, because rectifier G_5 is provided with a negative voltage. The positive pulse appearing at terminal A is passed by capacitor C_2 to the base of transistor Y. Due to the change-over of transistor Z to the non-conducting state, rectifier G_7 is supplied with a negative potential (like rectifier G_3 mentioned above), but due to the change-over of transistor X to the conducting state, rectifier G_6 is supplied with a positive potential. Even after the disappearance of the positive pulse at the base of transistor Y, this transistor cannot become conducting, no more than transistor Z can, because rectifier G_{10} is from then on supplied with a positive potential.

When the next positive pulse arrives at input terminal A of the distributor, transistor X becomes non-conducting and transistor Y conducting, whereas transistor Z remains non-conducting. Due to the arrival of a third positive pulse, the distributor reassumes the initial state.

The working of the networks in the lower part of the figure is as follows: At the first positive pulse arriving at input terminal A, transistor X becomes conducting, as a result of which there appears a positive voltage bound on rail 1. Consequently, a positive pulse is led via rectifier G_{12} and capacitor C_4 to the base of transistor P_1 , which is conducting normally, but which becomes non-conducting in this case for a period mainly determined by the value of capacitor C_4 . After this period, transistor P_1 becomes conducting again and delivers a 50 positive pulse at its collector.

When the next positive pulse appears at terminal A of the distributor, transistor Y becomes conducting and via conductor rail 2, rectifier G_{13} and capacitor C_5 , a positive pulse is applied to the base of transistor P_2 . This transistor P_2 too is conducting normally, but becomes non-conducting in this case for a period mainly determined by the value of capacitor C_5 . The positive pulse appearing at the collector of transistor P_1 will have no effect, if before its appearance a second positive pulse has reached input terminal A already, since in that case rectifier G_{15} from transistor P_2 is supplied with a negative potential.

If, however, the first positive pulse arriving at input terminal A is an isolated spurious pulse, the positive pulse appearing at the collector of transistor P_1 is led via rectifier G_{14} , capacitor C_6 and rectifier G_{16} to the base of transistor Q. Transistor Q too is in the conducting state normally and becomes non-conducting for some time in this case. So in this period: no collector current flows via rectifier G_{17} , the potential of point B is decreased, and the potential of the base of transistor R is decreased in consequence. Transistor R becomes conducting, thereby delivering a positive pulse to rail

5 conductor 4. As a result of this, transistors X and Y are put in the non-conducting state via rectifiers G_4 and G_8 , so that transistor Z assumes the conducting state, since its base potential is no longer increased via rectifiers G_{10} and G_{11} . The distributor has returned to its initial state. Transistor Q becomes conducting again and after a delay determined by the value of capacitor C_7 and the reverse resistance of rectifier G_{18} , transistor R becomes non-conducting. Yet transistors X and Y are kept in the non-conducting state via rectifiers G_3 and G_5 , respectively, until a fresh positive pulse is received at input terminal A.

15 If, however, there arrives at terminal A an isolated spurious impulse pair, not the positive pulse from the collector of transistor P_1 , but the one from the collector of transistor P_2 will be passed to the base of transistor Q, as a result of which the distributor returns to the initial state. The return to the initial state should be effected after a period following the spurious pulses 20 which is longer than the longest interval occurring between two successive normal pulses. The values of condensers C_4 and C_5 should be chosen accordingly.

It will be clear that distributor stages and networks 25 may also be composed with the aid of npn transistors or tubes. Further the arrangement may be such that in each state of the distributor more than one tube or transistor is conducting.

If e.g. a five-stage distributor has in each state two 30 conducting pnp transistors, the rail connected to transistor R should be connected via rectifiers to input terminals of the three distributor stages that have a non-conducting transistor in the initial state of the distributor.

If an n -stage distributor is wanted that can still return 35 to its initial state after a series of $n-1$ spurious pulses, $n-1$ networks containing e.g. pnp-transistors $P_1 \dots P_{n-1}$ are required. The network containing transistor P_1 belongs then to the stage in which the pnp-transistor passes from the non-conducting state to the conducting state at the first positive pulse arriving at input terminal 40 A in the initial state of the distributor.

While I have illustrated and described what I regard 45 to be the preferred embodiment of my invention, nevertheless it will be understood that such is merely exemplary and that numerous modifications and rearrangements may be made therein without departing from the essence of the invention, I claim:

1. A self re-setting counter circuit comprising:
  - (A) a distributor having
    - (a) n stages each having two conductive states, and
    - (b) conductor means interconnecting said stages,
  - (B) less than n networks each having
    - (a) two conductive states,
    - (b) a time delay circuit, and
    - (c) a connection to a corresponding one of said distributor stages; and
  - (C) a gating re-set circuit means controlled only by said networks to re-set all said stages in said distributor in their initial condition provided said distributor has not been brought into its next position within a predetermined time determined by the time delay circuit in one of said networks.
2. A counter according to claim 1 wherein each of said stages and each of said networks and said gating circuit includes a transistor.
3. A counter according to claim 1 wherein said time delay circuits comprise resistor-condenser circuits.
4. A self re-setting impulse counter circuit comprising:
  - (A) a distributor having
    - (a) n stages each having
      - (1) two conductor states,
      - (2) an input, and
      - (3) an output,
    - (b) conducting means to connect the input of each stage to the output of the previous stage in rotation, and

- (c) a common input connection to the input of each stage for the impulses to be counted;
- (B) less than n networks each having
  - (a) two conductive states,
  - (b) a time delay circuit, and
  - (c) a connection to a corresponding one of the outputs of said distributor stages; and
- (C) a gating re-set circuit means having
  - (a) an input terminal connected to and controlled by said networks, and
  - (b) an output terminal connected to each of said less than n stages corresponding to said less n networks of said distributor to re-set all of said stages in said distributor in their initial condition provided said distributor has not been brought into its next position within a predetermined time determined by the time delay circuit in one of said networks.

5. A counter circuit according to claim 1 wherein there are $n-1$ networks.

6. A counter circuit according to claim 4 wherein there are $n-1$ networks.
